UNITED STATES PATENT OFFICE.

ALVIN D. KEENE, OF PITTSBURGH, PENNSYLVANIA, ASSIGNOR TO WESTINGHOUSE ELECTRIC & MANUFACTURING COMPANY, A CORPORATION OF PENNSYLVANIA.

HEAT-TREATING FURNACE.

Application filed October 15, 1923. Serial No. 668,499.

My invention relates to electric furnaces and particularly to high temperature electric furnaces for heat-treating metal objects.

One object of my invention is to provide an electric furnace of relatively simple and compact construction that shall have a heat source of relatively high temperature.

Another object of my invention is to provide an electric furnace comprising a heating chamber and a resistor located entirely within a single refractory member.

In practicing my invention, I provide a refractory casing enclosing a heating chamber within which is located a single refractory member having a heat-treating chamber and one or more heating chambers within each of which there is located a resistor to provide the necessary heat.

In the single sheet of drawings, Figure 1 is a view, in vertical longitudinal section, of an electric furnace embodying my invention, and

Fig. 2 is a top plan view of a refractory member embodying the heat treating and the heating chambers.

A furnace structure 11 comprises an outer casing 12 that may be built up of suitable heat-insulating refractory material, either in the form of bricks or blocks or of a mass of such material. An inner lining 13 is provided within the outer casing 12 and it comprises either a unitary mass or a plurality of bricks or blocks of a suitable high-temperature resisting refractory material usually employed in the art.

A cover member for the furnace structure comprises an outer casing 15 of substantially the same construction as the casing 12 and an inner lining 16 of substantially the same construction as the inner lining 13. This cover member is made removable from the rest of the furnace structure to permit of easy access to a chamber 17 that is located within the inner lining 13.

A carbonized lining 18 is provided within the chamber 17 and it has located therein a single block of refractory electric-conducting material 19. The block 19 may be made of carbon or graphite and, as illustrated in the drawings, is of substantially rectangular contour in longitudinal section and may be of either square or rectangular cross-section. The block 19 is provided with a central lateral chamber 21 and with a plu-

rality of lateral chambers 22 and 23 located 55 adjacent to the ends of the block 19.

Elongated carbonaceous electrodes 24 extend through suitable openings 25 in the cover portion of the furnace and into the respective chambers 22 and 23. Means for 60 adjustably supporting the respective electrodes 24 comprise screw-threaded, vertically extending rods or shafts 26 having a supporting means 27 mounted on the cover member and provided with hand-wheels 28 65 at their upper ends. A clamping means 29 holds the respective electrodes 24 in their proper operative position relatively to the block 19, substantially as illustrated in Fig. 1 of the drawings, and permits of varying 70 the position thereof when required.

Supply circuit conductors (not shown) are electrically connected to the electrodes 24 and an electric current traverses the two electrodes and the block 19 in series circuit 75 relation, an arc being formed between the electrodes and the block within the two chambers 22 and 23. This type of heating element has been more particularly described and claimed in my co-pending application, Serial No. 658,031, filed August 18, 1923, and assigned to the Westinghouse Electric & Manufacturing Company, to which application reference may be had for further details of construction and of operation of 80 this type of furnace.

In general, it may be here noted that any arc formed occurs between the end of the electrode and the block 19 at substantially the bottom of the chamber 22 or 23, whereby 85 a substantially protected arc is provided and such arc will operate for a relatively long period of time without necessitating an adjustment of the elongated electrode 24.

The temperature of the arc is relatively 90 very high but there is a relatively large temperature gradient between the heating chambers 22 and 23 and the work-receiving chamber or compartment 21, and adjustment of the position of the electrodes makes it possible to obtain substantially any desired temperature within the chamber 21. Elongated metal objects to be heat treated, such as indicated by a rod 31, are placed in their proper operative positions within the chamber 21 and a bushing 32, of a suitable high-temperature resisting refractory material, is provided above the chamber 21 to suitably 100 105

protect the carbonaceous material of the block 19 against oxidation.

Protecting bushings 33, of carborundum, may be located above the heating chambers 22 and 23 to aid in protecting the electrodes 24 and the outer end portions of the block 19.

Where a relatively large number of elongated metal objects of one shape or form are to be heat treated, such as for instance, drill bits, a furnace of the hereinbefore described type is very effective. As the temperature of the heat source is relatively very high and the mass of the furnace structure is relatively small, a furnace of this type can be brought up to operating temperature in a very short time, particularly so, as by proper adjustment of the electrodes, a relatively large amount of energy may be translated into heat within the furnace structure in the initial periods of operation.

After the proper temperature has been obtained in the heat treating chamber, proper adjustment of the two electrodes to reduce the amount of energy translated into heat permits of maintaining the desired temperature within relatively small limits of varia-

tion and without making too great demands upon the operator's time for adjusting the electrodes.

Various modifications and changes may be made herein without departing from the spirit and scope of the invention, I desire, therefore, that only such limitations shall be placed thereon as are imposed by the prior art or are specifically set forth in the appended claim.

I claim as my invention:

An electric furnace comprising a single block of refractory electric-conducting material having a plurality of spaced and laterally extending openings therein, the intermediate opening constituting a heating chamber, an elongated electrode extending into each of said outer openings and co-operating with the walls thereof to produce an arc and a refractory high-temperature resisting casing surrounding said block of material.

In testimony whereof, I have hereunto subscribed my name this 9th day of October, 1923.

ALVIN D. KEENE.
